UNITED STATES PATENT OFFICE.

PATRICK McFADDEN, OF PHILADELPHIA, PENNSYLVANIA.

SHAFT-TUG FOR HARNESS.

SPECIFICATION forming part of Letters Patent No. 293,052, dated February 5, 1884.

Application filed November 19, 1883. (No model.)

To all whom it may concern:

Be it known that I, PATRICK McFADDEN, a citizen of the United States, residing at Philadelphia, in the county of Philadelphia and State of Pennsylvania, have invented certain new and useful Improvements in Shaft-Tugs for Harness; and I do hereby declare the following to be a full, clear, and exact description of the invention, reference being had to the accompanying drawings, which form part of this specification, in which—

Figure 1 is an elevation of tug with my improvements applied. Fig. 2 is a perspective of stirrup, and Fig. 3 a perspective of roller-plate.

My invention has for its object to provide an anti-friction attachment for harness-tugs, which said attachment can be readily applied to tugs of ordinary construction, and which will permit replacement of parts when worn out.

My invention consists of a metallic stirrup adapted and designed to be secured internally to a harness-tug, and provided with an anti-friction roller carried on a detachable plate.

Referring to the accompanying drawings, A represents a leather or other harness-tug, which may be of the usual or any other desired construction.

B is a metallic stirrup or piece, of substantially U shape, tapering or diminishing in thickness from its middle portion to the ends. Said stirrup is attached to the tug, inside the

shaft-opening *a* of the latter, by rivets *b b*, or 35 in any other equivalent or suitable manner. The middle or lower portion of the stirrup B is slotted, recessed, or formed with an opening, *b'*, and above the same is placed a plate, C, having lugs *c c*, affording bearings for an 40 anti-friction roller, D. Said plate C is also slotted at *c'* to afford play-space for the roller D, which latter also extends down into the opening or recess in the stirrup B. The shaft or thill of the vehicle, which enters the tug, 45 rides upon the roller D, and the plate C is secured to the stirrup B by rivets *c' c'*, or by equivalent means, which will permit its detachment from said stirrup when said plate or roller becomes worn out or otherwise impaired 50 for use.

What I claim as my invention is as follows:

1. In combination with recessed or slotted stirrup B, the plate C, having lugs *c c* and slot *c'*, and the roller D journaled in said lugs, 55 substantially as described.
2. The combination, with tug A, of slotted or recessed stirrup B, secured inside said tug by rivets *b*, and slotted plate C, having lugs *c c*, supporting an anti-friction roller, D, 60 substantially as shown and described.

In testimony that I claim the foregoing I have hereunto set my hand this 13th day of November, 1883.

PATRICK McFADDEN.
